LADY'S ORNAMENTED STOCKING

Ellen Troy, New York, N. Y.

Application January 9, 1951, Serial No. 13,717

Term of patent 7 years

(Cl. D47—7)

To all whom it may concern:

Be it known that I, Ellen Troy, a citizen of the United States of America, residing at New York, county and State of New York, have invented a new, original, and ornamental Design for a Lady's Ornamented Stocking, of which the following is a specification, reference being made to the accompanying drawing, forming part thereof.

Fig. 1 is a front elevational view of the stocking showing my new design;

Fig. 2 is an enlarged cross-sectional view taken along lines 2—2 of Fig. 1.

I claim:

The ornamental design for a lady's ornamented stocking, substantially as shown.

ELLEN TROY.
